PRESSING MACHINE LIGHT

Francis S. Latham, Killeen, Tex.

Application July 22, 1936, Serial No. 91,999

1 Claim. (Cl. 240—2)

The invention relates to a pressing machine light and more especially to a treadle operated switch for an electric light used on pressing machines.

5 The primary object of the invention is the provision of an electric light of this character, wherein the same is arranged upon a clothes pressing machine and is controlled by a switch operated from the treadle or pedal of the machine so that when the top presser head is in elevated position the light will be on and on the lowering of said head such light is extinguished, thus being convenient for the user of the machine in making inspection of the work pressed and 10 eliminating hand turning on and off of such light.

A further object of the invention is the provision of a light of this character, wherein the same is susceptible of adjustment so that it can 20 be properly located for inspection of the work during the pressing thereof and will be turned on and off automatically.

A still further object of the invention is the provision of a light of this character, which is 25 simple in construction, thoroughly reliable and effective in operation, and inexpensive to manufacture and install.

With these and other objects in view, the invention consists in the features of construction, 30 combination and arrangement of parts as will be hereinafter more fully described, illustrated in the accompanying drawing, which discloses the preferred embodiment of the invention and pointed out in the claim hereunto appended.

35 In the accompanying drawing:

Figure 1 is a side elevation of a pressing machine showing the light constructed in accordance with the invention applied thereto.

Figure 2 is a vertical sectional view through 40 the switch box showing the switch for controlling the electric current to the light in closed position.

Figure 3 is a view similar to Figure 2 showing the switch open.

Similar reference characters indicate corresponding parts throughout the several views in the drawing.

Referring to the drawing in detail, A designates generally a pressing machine for pressing clothing or other articles and includes a stationary 50 pressing bed 10 and a vertically swinging presser head 11, respectively. The presser head 11 is actuated from a foot treadle 12 as is usual.

Mounted on the frame of the pressing machine A is an electric light bracket 13 having an adjustable standard 14 of the flexible tubular kind

supporting an electric lamp 15 which is adjustably fitted with the standard 14 as at 16. This lamp 15 has a hand switch 17.

Included in the electric circuit 18 to the lamp 15 is a blade switch 19 opened and closed by a 5 trigger 20 projected beneath the treadle 12 and such switch 19 is opened by the said treadle on the depressing of the latter for the lowering of the head 11. When the treadle 12 raises the switch 19 closes, the said trigger 20 being connected to a coiled retractile spring 21 which functions to close the switch 19 when relieved of pressure from the treadle 12 active upon the trigger 20. This trigger 20 is fixed to the blade of the switch 19, it being pivoted at 22 within 10 a switch box 23 secured within the frame of the pressing machine A as shown in Figure 1 of the drawing.

When the switch 19 is open the lamp 15 is extinguished this taking place when the presser 20 head 11 has moved downwardly onto the presser bed 10 then when the said head 11 is raised or elevated the switch 19 closes and the lamp becomes lighted.

The treadle 12 operates the switch 19 for the 25 opening thereof when such treadle is depressed and on the raising of the treadle the spring 21 becomes active for the closing of said switch 19. Thus it will be apparent that the lamp 15 is lighted and extinguished automatically yet it 30 can be turned off by the hand switch 17 when the head 11 is in raised position at the option of the user of the machine.

What is claimed is:

A light for a pressing machine having a stand 35 and a depressible foot treadle projecting forwardly of and from within the stand, comprising a fixture on the stand, an electric lamp adjustably held by said fixture, an electric circuit within the fixture and having the lamp therein, 40 a switch box on the stand at one side of the path of movement of the treadle, a switch within the box and included in said circuit and having a trigger for operation thereof extended beneath and in the path of movement of the said treadle 45 for vertical swing and actuation by said treadle, and a spring fixedly connected within the switch box at a point elevated to the trigger and having connection therewith for urging the said trigger in contact with the said treadle and 50 maintaining such contact at all times, the said trigger being insulated from the treadle and the said switch.
